UNITED STATES PATENT OFFICE.

GEORGE HOLT FRASER, OF BROOKLYN, NEW YORK.

SEPARATOR.

Continuation of application filed August 27, 1914, Serial No. 858,797. This application filed July 12, 1919. Serial No. 310,329. Renewed January 24, 1924.

To all whom it may concern:

Be it known that I, GEORGE HOLT FRASER, a citizen of the United States, residing at No. 226 Quincy Street, in the borough of Brooklyn, county of Kings, city and State of New York, United States of America, manufacturer, have invented certain new and useful Improvements in Separators, being a continuation of my original application Serial Number 858,797, filed August 27, 1914, renewed December 18, 1918, Serial Number 267,401, of which the following is a specification.

This invention relates to apparatus for separating, sizing or classifying, collecting or filtering materials by means of a fluid current, and aims to provide certain improvements therein.

Heretofore it has been common to separate fine from coarse material by an air current, by passing the material through a casing in which the current was drawn through the material to float out the fine particles and deposit these in a dust chamber, after which the current was returned and continuously re-used.

With apparatus of this character it has been difficult to prevent coarse particles from being carried out with the fine, and to prevent variation in product due to changing conditions.

This invention relates to apparatus in which a fluid current is utilized to effect separation, and aims to provide improvements whereby one or more products may be separated with greater convenience and certainty than heretofore.

To this end in carrying out the preferred form of the present improvements the material to be treated is formed into a descending blanket, alternately concentrated and expanded as it descends by gravity, intermittently retarded and re-distributed to avoid any undue acceleration, and sufficiently agitated to expose all portions to current action, and while subject to these conditions a fluid current is passed through it to float outwardly from the descending blanket all material capable of floating in the prevailing current. The remaining material descending through the current is withdrawn as tailings.

The extracting process to insure removal of all fine material involves the risk of carrying out some oversize, and this inven-

tion preferably provides for selecting from the extracting current such grade or grades of material as desired and insuring that the final product shall be free from objectionable sizes, and it also provides for more completely collecting the material of the desired fineness and more thoroughly filtering the returned fluid.

The invention further provides for more completely utilizing the space necessarily occupied by the apparatus, for outside current producing provision, for greater accessibility, and for convenience of cleaning, agitation and removal of parts, and it provides various features of improvement, all of which will be hereinafter more fully set forth, and described in detail in their preferred form, with reference to the accompanying drawings, which illustrate the preferred adaptation of my present invention, and in which—

Fig. 1 is a vertical axial section, cut approximately on the line 1—1 of Figs. 2 and 3 of an air separator constructed according to the preferred form of my invention, and

Fig. 2 is a horizontal section thereof cut approximately on the planes of the lines 2—2 of Fig. 1, and

Fig. 3 is a horizontal section thereof cut approximately on the planes of the lines 3—3 of Fig. 1.

Referring to the drawings:

Let A indicate the casing, B the driving mechanism, C the feed hopper, D the distributor, E the feed chamber, F the blower, G the dust chamber, H the return passage, I the coarse outlet, and J the fine outlet, of an air separator. All of these parts may be of any usual or suitable construction adapted to distribute the material in a descending blanket, cause a fluid current to traverse it, precipitate the fine material floated out by the current, continuously re-use the fluid medium, and separately deliver the coarse and fine products.

The casing A shown consists of a cylindrical body a, a flat top b, a conical bottom c, and a separable conical end d in which are formed the coarse and fine outlets, and all forming an enclosed chamber in which the fluid is confined.

According to one feature of my invention the driving mechanism comprises a tubular shaft K mounted in upper and lower bear-

ings *e* in a bracket *f* mounted on cross-beams *g* which support the separator. Slidingly or removably keyed or carried on the shaft *K* is a cone or step wheel *h* driven from a similar wheel *i* by a belt *j*, or other suitable variable speed driving provisions.

The shaft *K* has a shoulder *k* seating on a split collar *l* which supports it vertically on a ring, ball or other non-friction annular 10 thrust bearing *m*, which is centered upon and supported by the lower bearing *e*. The lower end of the shaft *K* is reduced so that it can be passed through the vertical bearing and extends into the casing, and has 15 screwed or otherwise separably connected to it a flange *o* to which the spider *p* is bolted or otherwise separably connected so as to revolve with the shaft.

The frame *f* is shown in Fig. 1 as open at 20 its front side so that the shaft may be removed horizontally and then raised vertically, it and the hopper above sliding horizontally into the open side of the frame.

The hopper *C* is rotatively and adjustably mounted on the frame *f* and has a tubular extension *q* telescopically and adjustably entering the feed pipe *L*, which latter is adjusted vertically by screws *r* and passes freely through the tubular shaft *K* opening at 30 its lower end opposite the feed disc *S* of the distributor from which it can be adjusted to regulate or control the speed of feed. This disc is adjustably and separably connected to the spider *p* by screws *n*, and revolves 35 with the shaft *K* so that material falling on it is thrown out centrifugally and horizontally into the feed chamber.

The distributor *D* may be any suitable device for feeding the material in a thin 40 blanket or wide thin stream, according to whether the blanket of material to be treated is to descend in a rectilinear or tubular path. It is preferably a driven member, and when the material is to descend by gravity 45 in the form of a tubular blanket the distributor is preferably revolved to throw it outwardly to its path of descent.

I prefer to form the feed chamber *E* as a circular or annular chamber surrounding 50 the distributor and bordered by a baffle plate shown as a cylindrical ring *t* against which the material strikes and which is removable for renewal.

Below the baffle ring my invention preferably provides a contracting or feeding ring or plate *u*, upon which the material falls from the baffle ring and by which it is directed inwardly and delivered onto the first of a series of retarding or distributing 55 rings or members *v* which check the speed of flow and deflect the material outwardly allowing it to fall onto a second converging or deflecting ring or plate *v* down which the material flows and from which it falls onto 60 the next plate *v*, the contracting and dis-

charging plates or rings being arranged in succession so that the material will flow down one and fall onto the other, be retarded thereby and again fall onto the next, and so on throughout the series of feeding plates 70 whereby the material descending by gravity between them traverses a sinuous path and is alternately retarded and re-started so that undue acceleration of speed of flow is prevented and sufficient agitation is obtained, 75 as the material descends between the plates. When these are arranged in ring form as shown the material descending between them constitutes an endless blanket or tubular envelope between the distributor and the inner upper cone *M* below them, and the space between the rings or plates constitutes an 80 annular sinuous separating passage *N*.

The rings *v* are relatively short and the rings *u* are preferably long or upwardly extended to bring their upper edges above the lower edges of the next upper ring *v*, and preferably to or above the lower edge of the next upper ring *u*, so that the current in passing between two rings 85 *u* must rise as it traverses the passage *O* and any heavy particles carried out horizontally by it may be dropped onto the upper part of the ring *u* as the current rises to pass over the top thereof.

For some work where further selection is unnecessary the series of rings *u* and *v* only may be used in connection with the current producing and dust collecting provisions, but I prefer to provide for further selecting 90 the material thus separated, and preferably for separately classifying or grading these selections according to their number. My invention provides for this one or more successive selectors, preferably annular and parallel with the primary feeding and retarding members and concentric with and surrounding these intermediate of the pressure and exhaust chambers. Preferably this is accomplished in the manner shown by 95 interposing a reversely inclined plate or ring *w* opposite each passage *O*, which intercepts the outflowing current and deflects it downwardly at an acute angle, so that the current 100 travels approximately horizontally and preferably slightly upwardly in a sinuous path as it expands outwardly, and large pieces carried by it will be intercepted and fall or be thrown out of it as the current turns 105 around the edges of the rings *w* in passing these. These rings are slightly spaced apart 110 above and below each passage to permit particles thus intercepted or selected to descend between them and are sufficiently spaced apart to give the desired width of passage 115 for the current. Particles extracted between these rings will descend crossing the current for each succeeding passage so that should any fines escape with them the current of a 120 succeeding passage may extract these.

Below the baffle ring my invention preferably provides a contracting or feeding ring or plate *u*, upon which the material falls from the baffle ring and by which it is directed inwardly and delivered onto the first of a series of retarding or distributing 55 rings or members *v* which check the speed of flow and deflect the material outwardly allowing it to fall onto a second converging or deflecting ring or plate *v* down which the material flows and from which it falls onto 60 the next plate *v*, the contracting and dis-

These rings or plates constitute a selector R.

Ordinarily one selector succeeding the initial separating device will suffice, but for some purposes a plurality of successive selectors, or differential classifiers or graders, may be desirable, and my invention preferably comprises further precipitation means successive to the initial extracting, which is preferably accomplished by providing around the passage O beyond the selector R, an outer receptacle or cone or wall z. The current from the several passages O discharges within this wall and flows upwardly over the top or open upper end y of the wall and down into the chamber Q. This wall z constitutes a second selector V, the tailings of which may be separately collected as shown by a cone W and passage X and outlet Y when this grade is desired.

Proportioning, inclination, relative elevation, and intermediate spacing, of these several parts will be suited to circumstances or requirements, but are preferably such as to effect varying current speeds as well as considerable changes of direction in the current as it progresses outwardly, and in the final selection chamber the area is sufficient to give such volume as will insure a current speed suited to float only particles of the fineness desired in the finest product to be produced so that only this will be carried into the chamber Q and can reach the dust chamber G.

In the chamber Q the current descends with comparative slowness, its floating dust being precipitated by gravity into the settling chamber for removal through the fine outlet.

The air is withdrawn from the chamber Q or returned to the chamber P through the return passage H, which communicates between these and preferably exhausts by suction from the inner side of the chamber Q.

I preferably provide for mechanical extraction or filtration of floating particles from the fluid intermediate of the chamber Q, and the return passage H, I prefer to provide a foraminous or interstitial wall between these through which the current must pass, and this is preferably a double wall or series of hollow troughs or plates disposed with their concave sides facing the chamber Q and their convex sides facing the inlet H and extending downwardly and outwardly from the cone W constituting the top wall of the return, the cone a' constituting its bottom wall. These plates b' are staggered in relation and spaced apart so that circuitous passages c' exist between them through which the current may flow while their hollow faces will provide a space in which particles may settle and descend without danger of being floated by eddies into the return.

The open lower ends of the troughs b' discharge into the dust chamber where there is practically no current sufficient to lift their dust. Thus the returning current is sufficiently freed from floating back fines to avoid any loss of efficiency on this score, so that the current may be strong enough to extract all the fines without danger of material loss of efficiency, and the selectors may be used to extract large pieces in such a strong current before they reach the dust chamber.

Any suitable current producing means and connection may be utilized with those features of my improvements already described, but I prefer to employ an outside blower or one separate from and independent of the feeder, and to drive this and the latter from the same source of power, preferably a motor Z, coupled to the shaft d' of the blower F, which shaft is shown as extended to the pulley i for driving the feeder.

The suction and discharge connections between the outside blower and the chambers Q and P may be made in any suitable way, but according to the preferred form of my invention I provide for utilizing centrifugal action to equalize the outflow and inflow of current and avoid undue variations or inequalities thereof, and to preserve a uniform suction throughout the exhaust chamber Q. This is preferably accomplished by connecting the suction pipe e' of the fan tangentially with an annular exhaust passage f' outwardly of and surrounding the distributing and contracting inlet g' of the return and communicating with the latter by a reverse passage h' over an intermediate annular dam i', so that the suction current from the trough f' will cause a rapid whirling action in the latter which will prevent excessive withdrawal of air at any one point around the sinuous annular passages communicating between this and the inlet passage H.

My invention provides a similar means for utilizing centrifugal force to equalize the blast as the current comes from the blower to the chamber P which is preferably accomplished by connecting the blast pipe j' of the blower tangentially to an annular blast chamber k' in which the blast will whirl and uniformly discharge over the inner wall of the lower receptacle or cone l' and down through the passage m' to the lower open end n' of the inner upper receptacle or cone M, through which as it rises it will still be subjected to some whirling action which will aid in avoiding excess of current at any one point.

In this way an outside blower as distinguished from one enclosed within the casing and revolving with the distributor may be utilized at a great saving of power and much simplification of construction, and the desired blower and distributor speeds and ad-

justments may be had independently, and the blower need not be subjected to great wear from direct contact with the material, as it can operate only on the cleanest air.

- 5 My invention provides for utilizing much of the space within the bottom cone which is not all needed for precipitation of dust, and preferably accomplishes this by locating both the annular suction chamber and its 10 communicating passages, and the annular blast chamber and its communicating passages as well as the intermediate selector passages, all within the dust chamber, and the blast chamber within the suction chamber, so that these all are concentrically superposed and compactly nested around the tailings and selector passages, and the blower may be placed where desired and suitably connected with them.
- 15 20 When used as separate passages the selector passages are preferably disposed between the suction and blast equalizers by a series of cones spaced apart to give the necessary intermediate passage and suitably connected 25 and separated for convenience and manipulation. As shown the cone o held on the cone d serves as the inner wall of the dust chamber G and connects with the outlet Y and with the secondary selector passage X .
- 30 35 Loosely setting on it is a reverse cone p' serving as the top of the latter passage and the inner wall of the suction chamber f' and loosely setting on this is a cone q' constituting one outer wall of the latter, the top wall of which is the cone r' , all of these cones being suitably supported and mounted so that each can be vibrated or lifted and is movable for cleaning.

- 40 The inner troughs b' are preferably rigidly connected to the cone W and supported at their lower ends against the cone a' , but the outer troughs are movably or elastically connected at their upper ends to the cone W as by springs c^2 , which poise them resiliently 45 so that they may quiver in use to clean themselves, and their lower ends bear against the cone c . The cone c is preferably sectionalized by a section f^2 separably connected so that it can be removed to permit the removal 50 of the interior cones.

- 55 The cone W above the filter troughs covers and seals the upper ends of these and of the spaces between them to resist downward flow of current or leakage of dust vertically of them, and the cone a' crosses the lower ends of the inner troughs and projects across the apertures between the troughs to resist upward flow of current or leakage of material longitudinally of them, but any other suitable means may be used to prevent leakage 60 longitudinally of the troughs and to cause the return current to flow through the horizontally inwardly extending current passages afforded by the apertures between 65 their faces to travel approximately at right

angles to the longitudinal extension of such faces, so that there may be the minimum of disturbance to the current voids or calms formed in front of these faces and they can serve as downward ways affording conduits 70 across and for conducting below and out of the path of the current intercepted particles and down which intercepted particles can slide without molestation and by which such particles can be safely conducted through 75 the inwardly returning current and directed into the dust chamber out of the current zone.

Where advisable the edges of the cones are slightly spaced to permit settling to 80 drift through and where necessary their edges are valved with a flap d^2 or flexible strip to avoid current leakage while permitting gravity flow of precipitated material.

85 The outer wall of the blast chamber is shown as a cone s' carrying the outlet I and serving as the inner wall of the passage T , and on this cone is mounted the cone t' which serves as the top wall of the blast chamber and isolates it from the passage. The cone M serves as one inner wall of the blast chamber and the reverse cone u' as its bottom wall. While these cones may be fixed 90 together I prefer to loosely separably and suitably connect and support them so that they may be readily vibrated, adjusted or removed. The spacers between them constitute impact or jarring posts or members, by hammering on which percussively they may be vibrated to loosen adhering material. 95 Adjustable separable screws e^2 under the cones o' and s' support these.

100 Jarring of the parts may be effected in any suitable way, as by occasionally hammering on the screws e^2 , but I prefer to continuously jar the parts as by providing a jarring post s^2 on the cone o' , and a swinging hammer t^2 which swings in the space between this cone and the outer cone f^2 and alternately strikes the post and the outer cone, and which is swung by a rod u^2 projecting into the path of and struck by the swinging knockers v^2 hinged to a revolving part w^2 fixed on the shaft of the blower F as shown 110 in Fig. 1.

115 My invention provides for accessibility to the several parts of the device by the operator without substantial manipulation, and for this purpose I preferably construct the tailings outlet I with a large tubular passage x' closed by a cover y' by opening which a man can crawl in and pass through the interior of the separator to adjust, repair or clean it. Similarly the suction and blast passages e' and j' are 120 made respectively with a door z' in direct line with them and of sufficient size to permit entrance of the body so that the operator can crawl in either the suction or exhaust equalizer.

Several cones are preferably suspended by rods A' from the top b and positioned centrally by divergent bars a² and b² from the side.

5 In operation the feed entering from the hopper C will be controlled by adjusting the feed pipe L toward the feed disc s or by regulating the speed of the latter by its driving mechanism. The current will be 10 controlled by the speed of the fan or by a butterfly valve B' or otherwise.

Current rising into the chamber P will flow out between the rings v, traverse the blanket of descending material, extract 15 the fines and float them out through the passage O. The selectors R and V when and if used will make their proper selections and classifications, and the floating fines passing these will descend through the 20 chamber Q and fall into the dust chamber G, the air carrying these being drawn through the filter and clarified on its way to the return passage H. The exhaust through the latter will be uniform. Any sediment 25 settling within the exhaust chamber will leak through the cracks thereof and fall into the dust chamber. The blast by reason of its centrifugal action will exert a uniform pressure as it flows over and under 30 the wall and rises within the cone M and into the chamber P. Any dust settling in the blast passage will leak through into the main tailings outlet. The feed and withdrawal will be constant, and once adjusted 35 to the work operation may continue without change regardless of variations in quantity and quality. A sufficient current to insure complete extraction can be used without danger since the selectors will eliminate any 40 large particles blown out at the first extraction. Efficiency will be increased by the internal filtration.

The bottom cone d can be uncoupled and removed for entrance or cleaning, and the 45 three adjacent cones can be removed with it through the large opening in the bottom cone e. The section f² of cone e can be removed and may carry with it all of the cones below the filter tubes.

50 It will be seen that my invention provides improvements which can be readily and advantageously availed of and it will be understood that the invention is not limited to the particular details of construction, arrangement 55 or combination of parts, set forth as constituting its preferred embodiment since it can be utilized in whole or in part according to such modifications as circumstances or the judgment of those skilled 60 in the art may dictate without departing from the spirit of the invention.

When feed to the hopper C includes material too coarse for passing through the separator a scalper C' is used, which according to one feature of my invention is

composed of a slotted foraminous plate or screen bent into steps intermediate of the longitudinal extent of its elongated slots, so that the lower bent portion constitutes an outlet for each slot to permit escape of 70 nails or hanging pieces. This is disposed with its long faces or steps at approximately 45 degrees inclination and its intermediate portions at approximately right angles thereto, and mounted in a trough or chute 75 B' of greater inclination than the scalper. My invention provides a dam or retarder D' opposite each step to prevent too rapid flow. The large pieces scalped out of the feed descend past the separator to a spout E'. 80

The suction and blast pipes are separably connected to the blower, and the corresponding passages of the blower are provided with separable walls or hinged man-hole doors z', see Fig. 3, so that either can be opened or removed for access. 85

The scalper, having slots narrower than the selector outlets, guards these against possible oversizes.

What I claim is:

1. In combination, a casing enclosing a chamber, a receptacle in said chamber having upper and lower openings communicating with said chamber, means for passing pulverulent material to be separated into 95 said receptacle, means affording a way through said receptacle for the heavier particles of such material, means affording an endless current passage through and around said receptacle, means for circulating a fluid 100 medium through said passage to carry off into said chamber the lighter particles of such material, and substantially annular substantially vertically disposed foraminous filtering means across such passage and surrounding said receptacle for intercepting particles carried by such medium, said filtering means being constructed and arranged to conduct the intercepted particles across and below the path of the medium and affording inwardly extending current passages for such medium. 110

2. In combination, a casing enclosing a chamber, a receptacle in said chamber having upper and lower openings communicating with said chamber, means for passing pulverulent material to be separated into 115 said receptacle, means affording a way through said receptacle for the heavier particles of such material, means affording an endless current passage through and around said receptacle, means for circulating a fluid medium through said passage to carry off into said chamber the lighter particles of such material, and substantially vertically disposed foraminous filtering 120 means successive one to another across such passage for intercepting particles carried by such medium, said filtering means being constructed and arranged to conduct the in- 125

tercepted particles downwardly across the path of the medium and affording horizontally extending passages for such medium.

5. 3. In combination, a casing enclosing a chamber, a receptacle in said chamber having upper and lower openings communicating with said chamber, means for passing pulverulent material to be separated into 10 said receptacle, means affording a way through said receptacle for the heavier particles of such material, means affording an endless current passage through and around said receptacle, means for circulating a 15 fluid medium through said passage to carry off into said chamber the lighter particles of such material, and substantially vertically disposed foraminous filtering means across said passage and depending from said 20 receptacle for intercepting particles carried by such medium, said filtering means being constructed and arranged to conduct such 25 intercepting particles across and below the path of such medium and affording inwardly extending current passages for such medium.

4. In combination, a casing enclosing a chamber, a receptacle in said chamber having upper and lower openings communicating with said chamber, means for passing pulverulent material to be separated into 30 said receptacle, means affording a way through said receptacle for the heavier particles of such material, means affording an endless current passage through and around said receptacle, means for circulating a fluid medium through said passage to carry off into said chamber the lighter particles of such material, and substantially vertically 35 disposed foraminous filtering means across said passage and below said receptacle for intercepting particles carried by such medium, said filtering means being constructed and arranged to conduct such 40 intercepting particles across and below the path of such medium and affording inwardly extending current passages for such medium.

5. In combination, a casing enclosing a chamber, an upper receptacle within said 50 casing having upper and lower openings communicating with said chamber, means for passing pulverulent material to be separated into said upper receptacle, a lower receptacle affording a way for the heavier particles of such material and having an open 55 upper part affording communication between said chamber and said lower opening, means affording an endless current passage through and around said upper receptacle, 60 means for circulating a fluid medium through said endless passage to carry off into said chamber the lighter particles of such material, and substantially vertically disposed foraminous filtering means across said 65 passage and around said upper receptacle

for intercepting particles carried by such medium, said filtering means being constructed and arranged to conduct such intercepting particles across and below the path of such medium, and affording inwardly extending current passages for such medium. 70

6. In combination, a casing enclosing a chamber, an upper receptacle within said casing having upper and lower openings communicating with said chamber, means for passing pulverulent material to be separated into said upper receptacle, a lower receptacle affording a way for the heavier particles of such material and having an open upper part affording communication between said chamber and said lower opening, means affording an endless current passage through and around said upper receptacle, 75 means for circulating a fluid medium through said endless passage to carry off into said chamber the lighter particles of such material, and substantially vertically disposed foraminous filtering means across said passage and around said lower receptacle for intercepting particles carried by such 80 medium, said filtering means being constructed and arranged to conduct such intercepting particles across and below the path of such medium, and affording inwardly extending current passages for such medium. 85

7. In combination, a casing enclosing a chamber, an upper receptacle within said casing having upper and lower openings communicating with said chamber, means for passing pulverulent material to be separated into said upper receptacle, a lower receptacle affording a way for the heavier particles of such material and having an open upper part affording communication between said chamber and said lower opening, means affording an endless current passage through and around said upper receptacle, means for circulating a fluid medium through said endless passage to carry off into said chamber the lighter particles of such material, and substantially vertically disposed foraminous filtering means across said passage and between said receptacles for intercepting particles carried by such medium, said filtering means being constructed and arranged to conduct such intercepting particles across and below the path of such medium and affording inwardly extending current passages for such medium. 95

8. In combination, a casing enclosing a chamber, an upper receptacle within said casing having upper and lower openings communicating with said chamber, means for passing pulverulent material to be separated into said receptacle, a lower receptacle affording a way for the heavier particles of such material and having an open upper part affording communication between said chamber and said lower opening, means affording an endless current passage through 100

and around said upper receptacle, means for circulating a fluid medium through said endless passage to carry off into said chamber the lighter particles of such material, and 5 substantially vertically disposed foraminous filtering means across said passage and around said way and loosely disposed relatively to and concentrically of said lower receptacle, said filtering means being constructed and arranged to conduct such inter-

cepted particles across and below the path of such medium, and affording inwardly extending current passages for such medium.

In witness whereof, I have hereunto signed my name in the presence of two subscribing 15 witnesses:

GEORGE HOLT FRASER.
